UNITED STATES PATENT OFFICE.

JOSEPH B. TINSLEY, OF KANSAS CITY, KANSAS.

TURN-TABLE.

1,136,563.

Specification of Letters Patent. Patented Apr. 20, 1915.

Application filed June 2, 1914. Serial No. 842,435.

To all whom it may concern:

Be it known that I, JOSEPH B. TINSLEY, a citizen of the United States, residing at Kansas City, in the county of Wyandotte and State of Kansas, have invented certain new and useful Improvements in Turn-Tables; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in what are termed "turn-tables" of the type used in connection with railways for turning or reversing the position of locomotives.

The invention has for its object, primarily, to provide for actuating or turning the turn-table by the action or movement of the locomotive, thus avoiding doing this manually as heretofore.

A further object is to provide also for freeing or unlatching the turn-table preliminary to turning the same, also to again effect the latching or retention of the turn-table in position, as against unauthorized movement or turning, and to provide for doing this from the locomotive.

A still further object is to carry out the aforesaid ends with facility and expedition, and in the minimum time, devoid the manual labor or exertion of turning the turn-table.

The invention consists generically of means adapted to enable the turning of the turn-table after the locomotive has been run upon the table by the subsequent further movement of the locomotive thereon, carrying the turn-table therewith.

The invention consists further of sundry features, as accessories to that end substantially as hereinafter more fully disclosed and defined by the appended claims.

In the accompanying drawing is illustrated the preferred embodiment of my invention wherein it will be understood that various changes and modifications may be made with respect to the detailed construction and arrangement of the parts without departing from the spirit thereof, and in which drawing:

Figure 1 is a general plan view of my turn-table. Fig. 2 is an elevational view. Fig. 3 is a sectional elevation thereof, and

Figs. 4 and 5 are transverse vertical sectional views of the same taken upon the lines 4—4 and 5—5 of Fig. 1, respectively.

In the disclosure of my invention, I suitably devise a circular track 1 and a like inner or concentric track 2 of considerably less diameter, and above these circular tracks 1 and 2 is mounted a rectangular frame 3 upon suitable trucks or wheels 4 and 5 traveling upon the tracks 1 and 2, respectively. The wheels or trucks 4 are carried or journaled in suitable bifurcated pendent bearings 6 secured to the longitudinal members of the frame 3 coincidently with the track 1. The wheels or trucks 5 are carried by shafts 7 at their diagonally opposite ends suitably journaled upon the underside of the longitudinal members of the frame 3 so as to cause their wheels to travel upon the track 2.

Track-rails 8 alining the railway track-rails 9 are suitably secured or spiked into position upon transverse members 10 of the frame 3 serving in the capacity of ties, it being understood of course that the frame structure together with its carrying wheels or trucks and the circular tracks are all suitably depressed or sunken with respect to the surface to effect such alinement of the rails 8 with the track-rails 9.

The wheel-shafts 7 are intergeared by spur-gear pinions 11 secured to said shafts, respectively, for their conjoint or mutual rotation, while one of said shafts has fixed thereto a like pinion 12 of slightly greater diameter than the aforesaid pinions, and slidably mounted immediately in vertical alinement with the pinion 12 upon the frame 3 is a longitudinal rack 13 engaged by said pinion, said rack being held in keepers or guides 14 secured to the transverse members or ties 10, the purpose of which rack will be presently apparent.

Opposed edge-spaced apart jaws 15 are suitably or flexibly carried by and adapted to be moved with bars or rods 16 for engaging or receiving therebetween the desired wheel-axles or other available part of the locomotive when the latter is run upon the turn-table for enabling, as presently more fully seen, the turning of the turn-table by the movement of the locomotive. The bars or members 16 carrying the jaws 15 have their inner cylindrical ends let into sockets or bores in the ends of the rack 13 so as to turn therein, the opposite or other ends of

said jaw-carrying members being square or angular as shown for a purpose presently made apparent. Levers 17 are arranged at diagonally opposite ends of the frame 3 or 5 near said ends, whose fulcrums are the shafts 18 of beveled pinions 19, said fulcrums or shafts and pinions having fixed relation, the inner fulcrumed ends of said levers being equipped with latch-controlled detents 20 10 engaging toothed or notched segments 21 suitably fixed to the frame 3. The beveled pinions 19 mesh with somewhat less diametered beveled pinions 22 at right angles thereto, which latter are borne upon the inner ends of shafts 23 suitably journaled upon brackets projecting from the frame 3, the opposite ends of said shafts having sundry pivoted-together arm and link-connections, as at 24, 25 and 26 with the squared 15 or angular ends of the members 16 which carry the locomotive-axle engaging jaws 15, which latter, together with the rack 13, constitute the principal factors in effecting the turning of the turn-table through the movement 20 of the locomotive, which arm and link connections are clearly seen, particularly in Fig. 5.

The arms of the connections between the shafts 23 and the jaw-carrying members 16, 30 designated as 24 and 26, are fixed with respect to said shaft and said member to which they are connected, respectively, therefore are constant in their movements, or the arcs described thereby, accordingly controlling 35 the movement of the link 25, the other member of said connection thus providing for a uniform positive action of the jaws 15 directly actuated by said connections. The duplicating of the lever 7 and adjunctive-parts, 40 together with the locomotive-axle-engaging jaws 15, it is understood, is to provide for the adaptation of the device for use from either end.

Foot blocks or locks 27, pivoted laterally 45 to the frame 3 at its ends and adapted to drop into notches 28 produced in sills 29 and catching or taking thereover, provide for suitably anchoring or retaining the turn-table in position, this arrangement also being duplicated for each end of the turn-table, 50 for obvious reasons. A manually actuated lever 30 is suitably fulcrumed laterally to the frame 3 to conveniently control the disengaging of the foot block or locks 27 from the sills 29 and reengaging the same with the latter; flexible or stout wire connections 55 31 and 31^a being effected between said lever and said foot locks or blocks and said lever suitably equipped with a latch-controlled 60 detent 32, said detent engaging a notched or toothed quadrant 33 suitably fixed to the frame 3.

From the foregoing description, taken in connection with the accompanying illustration, it is thought that the operation of the

device has been made fully apparent, it being only required to state, possibly, that the locomotive being run upon the turn-table, the requisite adjustments are readily made by suitably actuating the foot-lock controlling lever 20 and the jaw-controlling lever 7 for engaging the jaws with the locomotive wheel-axles; the engineer then requisitely actuating his throttle to give the locomotive just sufficient movement to cause the rack 13 to suitably engage the pinion 12 which will through the gearing 11 effect the turning of the turn-table, this being controlled by suitably actuating the lever 7 releasing the action of the jaws 15 upon the wheel-axles. 80

I claim:

1. A turn-table of the type described, equipped with means to provide for the running thereon of a locomotive or engine, means including jaws adapted to engage the locomotive wheel-axles, means adapted to bring said jaws into position to receive said axles, and means to effect connection between the locomotive and the turn-table whereby, with the movement of the former, the turn- 90 ing of the latter may be effected.

2. A turn-table of the type described, equipped with means adapted for the running of a locomotive or engine thereon, means including jaws to engage the locomotive wheel-axles, a member carrying said jaws, means for actuating said jaw-carrying member whereby said jaws may be brought into such engagement with said wheel-axles, and means geared to the truck-axles of said turn-table, said jaw-carrying member being adapted to engage and impart movement to said truck-axle geared means with the movement of the locomotive. 100

3. A turn-table of the type described, equipped with means adapted for the running of a locomotive or engine thereon, means including a rack geared to the truck-axles of the turn-table, jaws adapted to engage the locomotive wheel-axles, a carrying member for said jaws adapted to engage and move said rack longitudinally, and manually actuated means for axially moving said jaw-carrying member for effecting such engagement between said jaws and said locomotive wheel-axles with the movement of the locomotive. 110

4. A turn-table of the type described, equipped with means for running a locomotive or engine thereon, a rack geared to the truck-wheel-axles of the turn-table, jaws for engagement with the locomotive wheel-axles, a carrying member for said jaws having one end received within one end of and engaging said rack and an opposite angular end 125 portion, a manually actuated lever, a shaft geared to said lever, and link and arm connections between said shaft and said angular end portion of said jaw-carrying member whereby the latter may be actuated to effect 130

such engagement of said jaws with said locomotive wheel-axles, said rack being adapted to effect the actuation of the turn-table truck-wheel-axles with the movement of said 5 jaw-carrying member, the movement of the latter being effected by the movement of the locomotive or engine.

5. A turn-table of the type described, equipped with means for the running of a 10 locomotive or engine thereon, including angular foot-locks pivoted to said turn-table and adapted to engage a fixture, a manually

actuated lever fulcrumed upon said turn-table, flexible means of connection between said foot-locks and said lever, and means 15 for the retention of said lever in fixed position.

In testimony whereof, I affix my signature, in presence of two witnesses.

JOSEPH B. TINSLEY.
